Primary Examiner — Jennifer L Rempfer*Assistant Examiner* — Danielle Nichole Bowly**CLAIM**

The ornamental design for a baby nest pillow, as shown and described.

DESCRIPTION

FIG. 1 is a perspective view of a baby nest pillow showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the baby nest pillow where the baby nest pillow is in an open state;

FIG. 10 is a front elevational view of FIG. 9; and,

FIG. 11 is a rear elevational view thereof.

The broken lines in the drawings depict portions of the baby nest pillow that form no part of the claimed design.
